UNITED STATES PATENT OFFICE.

WILLIAM L. TAYLOR, OF BATTLE CREEK, MICHIGAN, ASSIGNOR TO JOHNSON AUTOMATIC SEALER CO., LTD., OF BATTLE CREEK, MICHIGAN, A PARTNERSHIP ASSOCIATION LIMITED OF MICHIGAN.

FILLING AND WEIGHING MACHINE.

Application filed October 14, 1921. Serial No. 507,687.

The present invention is an improvement in filling and weighing machines, and is particularly designed for use with the scales used in automatic weighing and packaging and, particularly, is an instrumentality used to handle material having non-free flowing characteristics.

Materials having a high water content such as soap powder and brown sugar; material the deliquescent properties of which are high, such as powdered sugar, corn starch and gypsum products; oily materials such as cocoa; fancy cake flour carrying milk, shortening, etc. that requires only the addition of water; allspice, ginger, mustard and nutmeg—present a problem in automatic packaging that has not heretofore been successfully solved. Indeed, these materials have, for the most part, been packed by hand, though some rather successfully by automatic machinery.

With soap powder, for example, the well known "Gold Dust" having 42% moisture, it has been found that the material could not be rapidly and surely fed from the hoppers into the packages on the scales because of the packing and lumping of the powder. This condition was intensified on days when atmospheric conditions were bad; and many attempts have heretofore been made by the art to solve the problem of an efficient hopper from which the soap powder could be efficiently and surely fed into the packages under all conditions. The present invention solves this problem for the first time.

The invention resides in a structure having an imperforate horizontal support on which the material is deposited from a chute or otherwise, with feeder agitators moving the material laterally along said surface and into a feed hopper in which is mounted a second feeder agitator. Preferably, a pair of such hoppers are provided, one for the rough load and the other for the drip stream. The bottom of the hopper or hoppers is or are closed by a suitable gate or shutter. The feeder agitator that moves the soap powder into the hoppers from the imperforate support is run much slower than the feeder agitator in the hoppers. All of these feeder agitators operate only when the hoppers are open and the material is flowing

into the packages or other receptacles. Further, if a pair of hoppers are employed, one for the rough load and the other for the drip stream, the former is preferably operated faster than the latter.

The invention will be better understood by reference to the accompanying drawings, illustrating one expression of the inventive idea, and wherein

Fig. 1 is an end elevation;

Fig. 2 is a plan view;

Fig. 3 is a front elevation with part of the casing broken away to show the feeder agitators;

Fig. 4 is a perspective view showing the driving connections for the various feeder agitators and the means for operating the hopper closures;

Fig. 5 is a vertical section on the line 5—5 of Fig. 2; and

Fig. 6 is a detail of one of the hopper closures.

Referring to the drawings, wherein like reference numerals indicate like parts, 10 is a main hopper or receptacle into which the material is fed from a chute (such as a tapered pipe larger at the bottom than at the top, or otherwise) through opening 11 centrally disposed in the top of the same. The material falls on an imperforate surface 12 immediately under said opening 11. This surface is preferably curved in cross section as clearly shown in Fig. 5. The material is fed laterally along this surface into a pair of auxiliary feed hoppers 13 and 14 from which it is fed into the packages or receptacles to be filled. As herein illustrated, 13 is the rough load hopper and 14 is the drip stream hopper, and said hoppers, together with the main receptacle, form a unit disposed above instrumentalities to be presently described. The bottom of hopper 13 is provided with a closure 15 and hopper 14 with a closure 16.

The portable containers or receptacles to be filled are moved along a way or support 13' (Fig. 3) by any suitable conveyor such as a chain or belt 14' provided with pushers 15', and said way preferably includes the scale platform 16', 16'' disposed below hoppers 13 and 14. The conveyor may be operated in a manner well understood in the art to move the portable containers or cartons

- intermittently in the direction of the arrows, each container stopping momentarily under hopper 13 to receive the rough load, after which the container is moved below hopper 14 where it stops momentarily to receive the final load and is finally weighed. As herein shown, two containers are positioned under the hoppers so as to simultaneously receive material therefrom, other containers are in position to be moved under the hoppers, and a filled and weighed container has been pushed off the scale platform 16" for delivery to a top-sealing machine or other instrumentality (not shown).
- 15 The means for feeding the material through the main and auxiliary hoppers into the cartons or other portable containers preferably comprises the following devices. Mounted in the end walls 17 and 18 of the 20 main hopper is a shaft 19 on which is mounted a plurality of feeder agitators 20 preferably in the form of stout curved wires. The wires on the right hand side of the center of the main hopper feed the material into 25 the feed hopper 13 and those on the left into feed hopper 14. These wires are spaced and arranged so that they not only feed the material, but also simultaneously agitate the same and break all lumps; and the wires 30 are arranged to closely approach the walls so that the same are kept clean and free from accumulations. As illustrated, these wires pass through openings in the shaft 19 and each is held in place by any suitable means 35 as a set screw 21. Any suitable number of wires 20 to effectively feed and agitate the material may be utilized, this depending somewhat on the particular kind of material being handled.
- 40 The end walls 17 and 18 of the main hopper exactly coincide with the end walls of the feed hoppers 13 and 14, thus preventing any accumulation of material at these points.
- 45 In feed hopper 13 is mounted a shaft 23 which carries a plurality of similar feed agitators 24. As herein illustrated, four are employed though the number may be varied. The end wire 20' on shaft 19 is directly over the feed hopper 13 and may operate in the same, the rotation of shafts 19 and 23 being so timed that wires 20' and 24 do not clash.
- 50 In hopper 14 is mounted a shaft 25 carrying wires 26 as in the arrangement in hopper 13. Indeed, except for a different speed of rotation of shaft 25, the construction and operation of the two hoppers are preferably alike.
- 55 The various feeder agitators are rotated only when the closures 15 and 16 have been moved to open position, and shaft 19 is rotated only fast enough to fill the hoppers 13 and 14. As low as about 10 revolutions per minute has been found sufficient. Shaft 23 in the rough load hopper is rotated at 60 high speed, while shaft 25 in the drip feed
- hopper 14 is rotated at a slower speed. Speeds of 240 R. P. M. for the former and 200 R. P. M. for the latter have given satisfactory results in handling soap powder.
- 55 Shaft 19 carries a gear 27 that meshes with a pinion 28 on stationary shaft 29. Pinion 28 runs loose on shaft 29 and is keyed to a pulley 30 around which passes a belt 31 which latter also passes around a pulley 32 on a short shaft 33 carried in standards on the scale frame 34. Shaft 33 is driven from main shaft 35 (driven from the motor) of the scale through suitable connections, as sprocket chain 36 and sprocket wheel 36' and 36" on shaft 33 and shaft 35, respectively, the latter sprocket 36" being loose on shaft 35 and clutch-controlled, in a manner well known in the art.
- 60 Shaft 25 in the drip stream hopper 14 is driven from shaft 33 through a sprocket 37 chain 38 passing around sprocket wheels 38 on shaft 33 and sprocket wheel 39 on shaft 25. The shaft 25 is operated intermittently by means of a cam 70 that engages a roller 71 carried in one arm of a clutch lever 72 pivoted at 73, said clutch being associated with sprocket 36"; and the shaft 23 is operated intermittently by means of a similar clutch mechanism (not shown) mounted on shaft 35, and associated with sprocket 44.
- 65 Shaft 23 in the rough load hopper is driven from a short shaft 40 which is mounted on the side of the machine remote from shaft 33 (Fig. 4). This shaft 40 drives shaft 23 through sprockets 40' and 23' 100 and sprocket chain 41, and is in turn driven from shaft 35 through sprocket chain 42 which passes around a sprocket 43 on shaft 40 and sprocket 44 on shaft 35, the latter sprocket 44 being loose and clutch-controlled, 105 in a manner well known in the art.
- 70 The bottom of hoppers 13 and 14 are preferably curved in cross-section and each is provided with a pair of slides 45 and 46 (Figs. 1 and 6) which are moved toward and 110 from each other either manually or otherwise, in guides 47 and 48 to regulate the size of the opening. The closures or shutters 15 and 16 are preferably identical in construction. As here shown, each has a pair of flanges 49 and 50 to which is attached one 115 end of a pair of arms 51 which swing loosely on shaft 25. Links 52 and 53 are connected at one end to the shutter and at the other end to the sides of the feed hopper. 120
- 75 Arms 51 are rocked to move the shutter 16 by a cam 54 on shaft 35, said cam engaging one end of a lever 55 pivoted at 56, the upper end of said lever being connected through link 56' to the lower end of arm 57 with 125 which arm 51 swings loose on shaft 25, arms 51 and 57 being fastened to a collar 58 so that said arms and collar rotate together under the influence of cam 54. As shown at the left in Fig. 4, arms 51 and 57 and 130

sleeve 58 are connected by a key 58', these parts at this point being spread apart or separated to show the construction.

The shutter 15 for the rough load hopper 13 is identical with that just described but is driven from cam 59 on shaft 60 which latter is driven from shaft 35 by sprocket chain 61 passing around sprocket wheels 60' on shaft 60 and 35' on shaft 35. Said cam acts on a roller 62 carried in one end of arm 63 pivoted on shaft 64 which latter has rigidly secured thereto one end of arm 65, the upper end of which is connected to one end of link 66. The other end of said link 15 is connected to the end of arm 67 mounted loosely on shaft 23 and connected to arm 51, the function of which is the same as that of arm 57. The links 56' and 66 are preferably made in two parts, an adjustable connection 20 being provided at 66' (Figs. 2, 3 and 4).

For purposes of inspection and access, the hopper is provided with a pair of pivoted doors 68 and 69 (Fig. 3) these being arranged directly over the feed hoppers.

25 The operation of the device is as follows:

The slides 45 and 46 are first opened to the desired extent. The material is then introduced into the main hopper through the orifice 11 and is fed laterally along the surface 12 into the rough load hopper 13 and the drip stream hopper 14. Through the connections described the feeder agitators, both in the main hopper and the feed hoppers, are rotated only when the shutters 15 and 16 have been moved as described to open the bottoms of said hoppers 13 and 14. Accordingly, the material, even soap powder with a 42% moisture content, is fed into the cartons freely and in a finely divided condition, even on days and under conditions when it is impossible to package the material on other automatic machines. When a rough load hopper and a drip stream hopper are employed the feeder agitators in the former are preferably rotated at a higher speed than the feeder agitators in the latter.

While one embodiment of the inventive idea has been herein shown and described in great detail, it is to be understood that the invention is not limited thereto but that various modifications may be made within the limits of the appended claims. For example, if desired, only one feed hopper may be employed as it will sometimes happen that one will answer all the requirements, as on a gross weight scale. Further, while the inventive idea has been shown as embodied

in a hopper or hoppers for a scale, it is to be understood that the improvement may be used for feeding materials in other relations. 60

What is claimed is:

1. In combination, a receptacle provided with an imperforate support on which the material is deposited, feed hoppers arranged at each extremity of said support, feeding 65 and agitating means removing the material periodically from said support into said feed hoppers, feeding and agitating means in each hopper, a shutter closing the bottom of each hopper, means periodically opening said 70 shutters, means driving said feeding and agitating means only when the shutters are open, means for driving the first-mentioned feeding and agitating means slowly, and means driving the individual feeding and 75 agitating means rapidly.

2. In combination, a support on which material is deposited, hoppers at opposed extremities of said support, a device for feeding material in opposite directions 80 along the support and into said hoppers, and means in each hopper operatively connected with said feeding device for discharging material from the hoppers into receptacles. 85

3. In combination, a receptacle having a support on which the material is deposited, a rough load hopper at one extremity of said support, a drip stream hopper at the opposite extremity of the support, means for feeding the material in opposite directions along said support and into said hoppers, a device at each hopper for discharging material from the same into a container, and mechanism operatively connecting the said 90 feeding means and discharging devices for driving the former slowly and the latter 95 rapidly.

4. In combination, a receptacle having a support on which the material is deposited, a rough load hopper at one extremity of said support, a drip stream hopper at the opposite extremity of the support, means for feeding the material in opposite directions along said support and into said hoppers, a device at each hopper for discharging material from the same, and mechanism operatively connecting said feeding means and discharging devices for driving the former 100 slowly and the latter at relatively different 105 high speeds.

In testimony whereof I have signed this specification.

WILLIAM L. TAYLOR.
